UNITED STATES PATENT OFFICE.

WILLIAM T. BEAZLEY, OF WHITNEYVILLE, CONNECTICUT.

DESIGN FOR A CHRISTMAS-TREE BASE.

Application filed February 16, 1926. Serial No. 16,545. Term of patent 3½ years.

To all whom it may concern:

Be it known that I, WILLIAM T. BEAZLEY, a citizen of the United States, residing in Whitneyville, county of New Haven, and State of Connecticut, have invented a new, original, and ornamental Design for Christmas-Tree Base, of which the following is a specification, reference being had to the accompanying drawing, forming part thereof, in which the figure is a view in perspective of the base.

I claim:

The ornamental design for a Christmas tree base as shown.

WILLIAM T. BEAZLEY. [L. S.]
